United States Patent

Des. 238,688

Patented Feb. 3, 1976

238,688

AQUARIUM

Samuel Shalom, 577 Grand St.,
New York, N.Y. 10002

Filed Jan. 21, 1974, Ser. No. 435,081

Term of patent 14 years

Int. Cl. D30—02

U.S. Cl. D30—8

FIG. 1

FIG. 2

FIG. 3

FIG. 4

FIG. 5

FIG. 6

FIG. 1 is a perspective view of an aquarium showing my new design;

FIG. 2 is a front elevational view;

FIG. 3 is a side elevational view;

FIG. 4 is a top plan view thereof;

FIG. 5 is a bottom plan view thereof; and

FIG. 6 is a cross sectional view taken along the transverse axis in FIG. 4.

I claim:

The ornamental design for an aquarium, substantially as shown and described.
